UNITED STATES PATENT OFFICE.

EDWIN N. LIGHTFOOT, OF NEW YORK, N. Y., ASSIGNOR TO THE CUTLER-HAMMER MFG. CO., OF MILWAUKEE, WISCONSIN, A CORPORATION OF WISCONSIN.

IGNITION DEVICE.

1,359,514.

Specification of Letters Patent.

Patented Nov. 23, 1920.

Application filed September 28, 1917. Serial No. 193,649.

To all whom it may concern:

Be it known that I, EDWIN N. LIGHTFOOT, a citizen of the United States, residing at New York, in the county of Bronx and 5 State of New York, have invented new and useful Improvements in Ignition Devices, of which the following is a full, clear, concise, and exact description, reference being had to the accompanying drawing, forming 10 a part of this specification.

This invention relates to ignition devices for internal combustion engines, and while not limited thereto, is particularly applicable to heavy oil engines designed to develop only moderate compressions and 15 therefore requiring, particularly during starting, some ignition means other than the heat incident to the combustion chamber pressure.

20 Since the ordinary high tension spark gap plug employed in gasolene engines to explode the more or less volatile charges there encountered does not develop sufficient heat for the ignition of heavy oil fuels, it 25 has heretofore been proposed to ignite the compressed charges, in engines of the character stated, by means of an externally heated "hot bulb" located within the combustion chamber. This method, however, 30 is open to serious objection, being incapable of providing exact heat regulation and involving an open flame with its attendant dangers.

Among the objects of the present invention is to provide an ignition device for the foregoing and other purposes wherein the aforesaid difficulties are obviated and the various parts are capable of more ready adjustment and renewal when necessary.

40 A further object is to provide a device of the character stated having means for varying the adjustment thereof at will.

A further object is to provide a device of the character stated wherein deterioration 45 of the parts subject to thermal action is retarded and renewal when necessary is facilitated, and the consumption of current is reduced.

Other objects and advantages will hereinafter appear.

According to this invention ignition of the heavy oil charge is effected through the heating effect due to localized resistance between a pair of electrodes arranged to maintain an electrically imperfect contact with

each other and traversed by a current of relatively low potential, such as that produced by a storage battery, whereby the temperature of said electrodes adjacent their points of contact is maintained sufficiently high to ignite the combustible mixture in contact therewith. 60

In the accompanying drawing,

Figure 1 is a view, partly in section, of an embodiment of the invention; while, 65

Fig. 2 is a fragmentary longitudinal sectional view thereof; and,

Fig. 3 is a similar view showing a slightly modified construction.

Referring to the drawing, the same discloses an ignition plug 1 extending within the combustion chamber 2 of an internal combustion engine of the character aforesaid. Said plug comprises in general a shouldered plug casing 3 penetrating the 70 chamber wall 4 and having an integral electrode portion 5 located within said chamber and adapted to coöperate with a relatively movable electrode 6 carried within said casing and insulated therefrom, together with 75 regulating means indicated at 7 for varying the relative position of said electrodes and a cap 8 surrounding said regulating means and electrically connected with said movable electrode but insulated from said 80 fixed electrode.

In practice the circuit connections for the electrodes 5 and 6 are preferably established by connecting the cap 8 with one side of a storage battery or other source of low voltage current, the other side of said source being grounded to a portion of the engine with which the plug casing 3 is in electrical contact. Current thus passes between said electrodes which are designed for coöperation 90 to form an imperfect or arcing contact, the resistance and consequent heating effect thereof being regulable by varying the relation of the movable electrode to the fixed electrode and particularly the pressure of 95 the former against the latter.

More particularly the plug casing 3 is provided with a longitudinal bore 9 extending throughout the greater portion of its length, the inner extremity of said casing 105 being left solid and constituting the fixed electrode 5. One or more apertures 10, which may assume various forms in practice, afford communication between the combustion chamber and the inner end of the 110

bore 9 which is preferably of reduced diameter as indicated at 11. Said casing is also counterbored to provide a shoulder 12 and interiorly threaded at 13 to receive a gland nut 14, and is furthermore exteriorly threaded at 15 for screwing within the chamber wall 4.

A sleeve 16, which surrounds and guides the movable electrode 6, is positioned within 10 said casing by means of an integral flange 17 clamped between the gland nut 14 and the shoulder 12 and separated therefrom by means of insulating washers 18 located therebetween, the inner end of said sleeve terminating just short of the reduced portion 15 of said bore.

The movable electrode 6 comprises a rod of carbon or other suitable material mounted to slide within the sleeve 16, the outer end 20 of said electrode being anchored within a socket member 19 also sliding within said sleeve. A cage 20 is secured to the outer end of said socket member, said cage surrounding a helical spring 21 which is adapted to 25 be compressed to a stud 22 screwed within the outer end of the sleeve 16 for varying the relation of said electrode to the fixed electrode 5, the engaging portions of said electrodes being suitably shaped to provide 30 a relatively high resistance at the point of contact therebetween.

For protecting the above described parts and preventing the escape of hot gases through the sleeve 16, the cap 8 is screwed 35 upon the projecting portion of the latter to abut the outer face of the gland nut 14, an insulating washer 23 serving to prevent electrical connection between said cap and said gland nut while a suitable washer 24 serves 40 to provide a gas tight joint therebetween. The outer end of the cap 8 is further provided with a suitable conductor terminal 25.

The stud 22 is operable to vary the pressure of the movable electrode against the 45 fixed electrode, furthermore upon retraction of said stud the pressure within the combustion chamber tends to force said movable electrode within the sleeve 16 and out of the hot zone of said chamber, after the engine 50 has begun firing automatically, thus reducing deterioration of said electrode. Obviously, if desired, the stud 22 and the electrode 6 may be connected to afford positive 55 means for retracting the latter, as by the means illustrated in Fig. 3.

In this construction the adjacent ends of the stud 22 and the electrode 6 are formed with projecting knobs 26 and 27 to be engaged by the respective ends of the spring 60 21 to facilitate withdrawal of said electrode by means of said stud, the latter being further provided with a knurled portion 28 for manual actuation.

By the construction described practically 65 the entire length of the movable electrode

is rendered available for use, and renewal, when finally necessary, is greatly facilitated. Moreover, owing to the concentration of the heated area, the current necessary to successful operation is minimized.

70

What I claim as new and desire to secure by Letters Patent is:

1. In an ignition device for internal combustion engines and the like, the combination with a combustion chamber, of a pair 75 of relatively adjustable electrodes extending therewithin and connected to a source of current, said electrodes being arranged to provide a localized resistance of imperfect contact and consequent heating effect there- 80 between and means tending to retain said electrodes in a predetermined relation.

2. In an ignition device for internal combustion engines and the like, the combination with a combustion chamber, of a pair 85 of relatively adjustable electrodes extending therewithin and connected to a source of current, said electrodes being arranged to provide a localized resistance of imperfect contact and consequent heating effect there- 90 between, means for normally maintaining said electrodes in a predetermined relation and enabling relative adjustment of said electrodes at will from the outside of said combustion chamber.

95

3. In an ignition device for internal combustion engines and the like, in combination, a plug casing associated with a combustion chamber, said casing having an interiorly located electrode surface in communication 100 with the interior of said chamber, an electrode carried within said casing for co-operation with said electrode surface to form a localized resistance of imperfect contact and consequent heating effect therebetween.

105

4. In an ignition device for internal combustion engines and the like, in combination, a pair of normally stationary electrodes associated with a combustion chamber, said electrodes being connected to a source of current and arranged to provide a localized resistance therebetween, the interior of said chamber being in communication with said localized resistance and means for removing certain of said electrodes from the region of 110 excessive heat of said chamber during the continuance of operative conditions within the latter.

115

5. In an ignition device for internal combustion engines and the like, in combination, 12 a plug casing to be screwed within the wall of a combustion chamber and having an electrode surface in communication with the interior of said chamber, a hollow sleeve carried in fixed and insulated relation within 12 said casing, an electrode slidably mounted within said sleeve, means for electrically connecting said electrode and said casing with a source of current, and means biasing said electrode to localized resistance forming re- 13

lation with respect to the electrode surface of said casing.

6. In an ignition device for internal combustion engines and the like, in combination, 5 a bored plug casing to be screwed within a combustion chamber and having a solid portion providing an electrode surface in communication with the interior of said chamber, a coöperating electrode movably mounted within the bore of said casing and means tending normally to maintain said movable electrode in a predetermined relation with respect to said electrode surface.

10 7. In an ignition device for internal combustion engines and the like, in combination, 15 a bored plug casing to be screwed within a combustion chamber and having a solid portion providing an electrode surface in communication with the interior of said chamber, 20 a coöperating electrode movably mounted within the bore of said casing, a spring tending normally to maintain said movable electrode in a predetermined relation with respect to said electrode surface and spring adjusting means for varying the relation therebetween.

25 8. In an ignition device for internal combustion engines and the like, in combination, 30 a bored plug casing associated with a combustion chamber and having a portion providing an electrode surface in communication with the interior of said chamber, a sleeve clamped within the bore of said casing and insulated therefrom, and an electrode 35 slidably mounted within said sleeve for co-operation with said electrode surface to form a localized resistance therebetween.

40 9. In an ignition device for internal combustion engines and the like, in combination, 45 a bored plug casing associated with a combustion chamber and having a portion providing an electrode surface in communication with the interior of said chamber, a sleeve clamped within the bore of said casing and insulated therefrom, an electrode

slidably mounted within said sleeve for co-operation with said electrode surface to form a localized resistance therebetween, a spring mounted within said sleeve and tending to maintain a predetermined relation between 50 said electrode member and a stud to be screwed within said sleeve for varying the tension of said spring.

10 10. In an ignition device for internal combustion engines and the like, in combination, 55 a bored plug casing associated with a combustion chamber and having a portion providing an electrode surface in communication with the interior of said chamber, a sleeve clamped within the bore of said casing 60 and insulated therefrom, an electrode slidably mounted within said sleeve for coöperation with said electrode surface to form a localized resistance therebetween, means associated with said movable electrode for 65 normally maintaining the same in a predetermined relation with respect to said electrode surface and enabling relative adjustment of the former and a cap to be screwed about said sleeve adjacent said casing. 70

11. In an ignition device for internal combustion engines and the like, in combination, 75 a bored plug casing associated with a combustion chamber and having a portion providing an electrode surface in communication with the interior of said chamber, a sleeve clamped within said casing and insulated therefrom, an electrode mounted within said sleeve and projecting therebeyond for coöperation with said electrode surface to 80 form a localized resistance, means for normally maintaining a predetermined relation between said electrode and said coöperating surface, said means permitting retraction of said electrode within said sleeve for protection of the former. 85

In witness whereof, I have hereunto subscribed my name.

EDWIN N. LIGHTFOOT.
